METHOD OF KEYING RADIO
TRANSMITTERS

Clarence W. Hansell and Hallan E. Goldstine,
Port Jefferson, N. Y., assignors to Radio Corporation of America, a corporation of Delaware

Application February 26, 1938, Serial No. 192,682

10 Claims. (Cl. 178—66)

This invention relates to the art of keying radio transmitters and discloses a novel method and means whereby the keying can be accomplished in a manner that will have the advantages of extremely high speed keying and can be used on fairly high power tubes without requiring a large amount of power to be dissipated in the absorbers or keying tubes. Keying speed is increased and efficiency improved in accordance with our invention by keying the grid of an amplifier tube the cathode of which is in the non-keyed state positive relative to the grid (also positive) sufficient to cause cut-off. The keying tube may be of smaller than normal rating and preferably is of a size such that with proper direct current connections between it and the direct current source and the grid of the amplifier tube, the anode direct current of the keying tube when conductive is substantially equal to the maximum grid current of the amplifying tube. Maintaining the grid positive permits the co-relation between the plate current of the keying tube and the grid current of the amplifier tube described above, and permits increased keying speeds to be obtained with reduction of lost or dissipated current in keying. The balancing of the keying tube current against the keyed circuit current improves the stability of the oscillator voltage and consequently its frequency of operation is improved. An additional feature which further increases the speed, efficiency and smoothness of operation is the use of non-linear resistance in the cathode returns of the oscillator, buffer amplifier and power amplifier. The oscillator cathode floats above ground due to the potential drop in the non-linear resistance and its grid being connected to its cathode by a self-biasing resistance it operates at constant bias and generates waves of constant frequency. Since the oscillator operates continuously this non-linear resistance produces a fixed bias for all of the tubes of the system. Moreover, the plate currents of the buffer amplifier and power amplifier are keyed between cut-off and full current and but for the action of the said non-linear resistances this would put a large variable voltage on the oscillator plate and consequently cause changes in the continuous wave frequency. The present invention and in particular the features mentioned above and the specification which follows, are applicable to all radio transmitters and in particular to radio transmitters, where high speeds such as facsimile are to be adequately handled. This new system which

produces the desired results is therefore very important.

In describing our invention more in detail reference will be made to the attached drawing wherein the single figure illustrates our novel means including the keyed buffer amplifier with the cathode at high positive potential, the circuit for balancing the grid current of the keyed tube against the current of the keying tube and the non-linear resistances.

By referring to the figure the details of operation can be more clearly described. A radio frequency amplifying tube 1 has its anode 8 connected to the positive terminal of a direct current source and its cathode 9 connected to the negative terminal of said source through Thyrite resistances so that the filament circuit 10 is maintained at a positive potential with respect to said negative terminal and ground. The grid 12 of this tube is connected to its radio frequency driving circuit 3 and from there is connected through suitable resistances 4 and 5 back to the positive terminal of the anode potential source. A keying tube 2 has its anode 14 connected to 4 and its cathode grounded so that it will draw current through resistor 4 when its grid is maintained at zero potential and will draw no current through resistor 4 when its grid is biased negative a substantial amount. Keying potentials from any source 16 are applied to the grid 18 of tube 2 to key the same so that tube 2 is alternately more conductive and less conductive. The source of continuous wave energy 20 may be coupled to 3 at 22 and may comprise a tube generator with its anode 24 connected to the source of direct current and its cathode 26 connected to the Thyrite resistance 29. The keyed wave energy is supplied from the anode 8 of tube 1 to a tuned circuit 28 and induced therefrom on 30 and the grids of a power amplifier tubes, the cathodes of which are also connected to the Thyrite resistance 29 as shown. The anodes of the power amplifier tubes are connected to the direct current source.

In operation, the key is closed on the negative potential terminal and the grid of tube 2 is held 200 v. negative. Tube 2 draws little or no current through resistor 4. However, current flows through 4 to the grid of 1 and the potential drop through 4 is such that a relatively high positive potential is applied to the grid 12 of tube 1. This potential is sufficiently near to the potential of the cathode 9 to make the tube 1 conductive so that wave energy is amplified and supplied to the power amplifier. The tube 1 is now conduc-

tive and due to the radio frequency drive impressed on its grid circuit 3 the grid will draw sufficient grid current to maintain this tube at a proper operating point. Now, if tube 2 is 5 made conductive by reducing its grid voltage to zero the tube 2 will draw sufficient anode current through resistor 4 to bias tube 1 to cut-off. For example, if we assume the grid of tube 1 around 200 or 400 volts positive since tube 1 10 filament is 2000 v. positive with respect to ground and its grid being, say, 400 v. positive, the grid therefore is 1600 v. negative with respect to the filament and the tube will be cut off at the peaks of the radio frequency voltage and will not over- 15 ride the 1600 v. bias. Since tube 1 is now cut off no wave energy is amplified therein and supplied to the power amplifier and the system is 20 on space.

The values given above are for illustration only 20 and the scope of the invention should not be limited by these figures. By adjusting the values of resistor 5 and resistor 4 a condition can be maintained where the grid circuit of tube 1 draws the same amount of current when it is conducting as 25 the anode circuit of tube 2 will draw when it is conducting and tube 1 is cut off. This means that there is essentially no change in plate current through resistor 4 between key down and key up condition or mark and space. The time 30 constant of this keying system is quite small due to the fact that the capacities in the circuit are relatively small, thus permitting high speed key- 35 ing.

Another feature of this particular keying 35 scheme is that Thyrite is used in the cathode return circuit of the tubes to obtain their bias. The oscillator tube in 20 runs continuously since it is not keyed and furnishes the fixed bias by means of the Thyrite 29 in its cathode circuit 40 for the other tubes. Only one rectifier is used to supply the plate voltage to the transmitter, thus eliminating the bias rectifier and the other lower voltage plate supply rectifier. The Thyrite resistors have a characteristic such that the po- 45 tential drop therethrough does not increase linearly with respect to current increase therethrough. Thus, switching of the buffer amplifier tube and power tube from little or no current to full current has less effect on the potential of 50 the common source and consequently less effect on the frequency of operation of the oscillator which draws its current from said source.

We claim:

1. In a telegraphy system, a wave energy am- 55 plifier having an electrode excited by continuous wave energy to be keyed and an output electrode coupled with a utilization circuit, a keying tube having an electrode connected with means for impressing thereon potentials of different value 60 to render said keying tube alternately more conductive and less conductive, said keying tube having an anode and a cathode, direct current circuits interconnecting the anode and cathode of said keying tube with an electrode in said wave 65 amplifier to bias said tubes to potentials such that when the keying tube is more conductive the amplifying tube is less conductive and vice versa, and means in said direct current circuits for limiting the current flow to said last named elec- 70 trode in said wave amplifier tube when conductive to a value substantially equal to the anode current flowing in said keying tube when it is conductive.

2. In a telegraphy system, a wave energy am- 75 plifier having a control grid excited by continuous wave energy to be keyed and an output elec-

trode coupled with a utilization circuit, a keying tube having a control grid connected with means for impressing thereon potentials of different value to render said keying tube alternately conductive and non-conductive, said keying tube 5 having an anode and a cathode, direct current circuits interconnecting the anode and cathode of said keying tube with the control grid of said continuous wave amplifier to bias said electrodes values such that when the keying tube is conductive the amplifying tube is non-conductive and vice versa, and means in said direct current circuits for limiting the current flow to said control grid electrode in said continuous wave amplifier tube when conductive to a value substantially 10 equal to the anode current flowing in said keying tube when it is conductive.

3. In a telegraphy system, a keying tube having a control electrode, a cathode and an auxiliary electrode, an amplifier having a control electrode, a cathode and an auxiliary electrode, means for maintaining the cathode of said amplifier positive with respect to the control electrode of said amplifier and the cathode of said keying tube, a source of direct current potential, 20 a direct current circuit interconnecting said source of direct current potential and the auxiliary electrode of said keying tube with the control electrode and cathode of said amplifier tube, a current limiting impedance in the control electrode to cathode circuit of said amplifying tube of such a value that maximum current flowing in said circuit is substantially equal to normal auxiliary electrode to cathode current in said keying tube, means for impressing continuous 35 wave energy on the control grid of said amplifying tube and means for varying the potential of the control grid of said keying tube between two values which alternately render said keying tube more conductive and less conductive to control 40 the direct current potential on the control electrode of said amplifier tube.

4. In a telegraphy system, a keying tube having a control grid, a cathode and an anode, an amplifier having a control grid, a cathode and an anode, means for maintaining the cathode of said amplifier positive with respect to ground, means for maintaining the control grid of said amplifier positive with respect to ground, a source of direct current potential, a direct current circuit interconnecting said source of direct current potential and the anode and cathode of said keying tube with the control grid and cathode of said amplifier tube, an impedance in the anode-to-cathode circuit of said keying tube, means for 55 impressing continuous wave energy on the control grid of said amplifying tube and means for varying the potential of the control grid of said keying tube between two values to vary the conductivity of said keying tube, and the variations 60 of potential drop in said impedance to vary the potential of said amplifier control grid relative to its cathode.

5. In a telegraphy system, a keying tube having a control electrode, a cathode, an auxiliary electrode, an amplifier having a control electrode and a cathode, means for maintaining the cathode of said amplifier highly positive with respect to ground, means for maintaining the control electrode of said buffer amplifier positive relative 65 to ground, a source of direct current potential, a direct current circuit including an impedance connecting said source of direct current potential and the auxiliary electrode and cathode of said keying tube, a connection between a point on 70

5 said impedance and the control grid and cathode of said amplifier tube, a current limiting impedance in said last named connection of a valve such that maximum current flowing in said circuit is substantially equal to normal auxiliary 10 electrode-to-cathode current in said keying tube, means for impressing continuous wave energy on the control grid of said amplifying tube and means for varying the potential of the control 15 electrode of said keying tube between two values which alternately render said keying tube conductive and non-conductive.

6. In a telegraphy system, an amplifier tube having a cathode and a control grid, means for impressing wave energy to be keyed continuously 15 on the control grid and cathode of said amplifier tube, a source of direct current potential, non-linear resistance means connecting the anode and cathode impedances of said amplifier to said 20 source of direct current potential, a keying tube having a control grid, a cathode and an anode, direct current circuits interconnecting the anode and cathode of said keying tube and the control grid and cathode of said amplifier tube with said 25 source of direct current potential, means in said last named circuits to limit the flow of direct current in the grid circuit of said amplifier tube such that a maximum it is substantially equal to the 30 direct current flowing in the anode and cathode of said keying tube, and means for keying the potential on the control grid of said keying tubes between values at which it is alternately conductive and non-conductive.

7. In a telegraphy system, an amplifier tube having an anode, a cathode and a control grid, means for impressing continuous wave energy to be keyed on the control grid and cathode of said 35 amplifier tube, a source of direct current potential, a power amplifier of the discharge tube type having an input coupled to said first amplifier anode and an output coupled to a utilization circuit, non-linear resistance means connecting the anode and cathode impedances of said power amplifier device and said amplifier to said source 40 of direct current, a keying tube having a control grid, a cathode and an anode, direct current circuits interconnecting the anode and cathode of 45 said keying tube and the control grid and cathode of said amplifier tube with said source of direct current potential, means in said last named 50 circuits to limit the flow of direct current in the grid circuit of said amplifier tube so that at maximum it is substantially equal to the direct current flowing between the anode and cathode of said keying tube, and means for keying the potential on the control grid of said keying 55 tubes between values at which it is alternately conductive and non-conductive.

8. In a telegraphy system, a keying tube having a control grid, a cathode and an anode, a buffer amplifying tube having a control grid, cathode and anode, an oscillator tube having a

control grid, cathode and amplifier and a power 5 amplifier tube having a control grid, cathode and anode, high frequency circuits coupling electrodes in said oscillator tube to the control grid of said buffer amplifier tube and the anode of said buffer amplifier tube to the control grid of said power amplifier tube, a source of direct current potential, a non-linear resistor, means including portions of said non-linear resistance connecting the cathodes of all of said tubes to the negative 10 terminal of said source of direct current potential, connections between the anodes of all of said tubes and the positive terminal of said source of direct current potential, an impedance in the connection between the anode of said keying tube 15 and said positive terminal, an impedance connecting the anode of said keying tube to the control grid of said buffer amplifier tube and a source of keying potentials connected between the control grid and cathode of said keying tube. 20

9. In a telegraphy system, a source of direct current, a source of continuous wave energy to be keyed comprising an electron discharge tube having electrodes connected in alternating current circuits and in a direct current circuit including a non-linear resistance in series with said source of direct current, an amplifier tube having a cathode connected to a point on said non-linear resistance positive relative to ground or equivalent potential and an anode connected to 30 said direct current source whereby said cathode is maintained at a substantially fixed potential relative to ground due to the continuous operation of said discharge tube, means for impressing wave energy from said discharge tube on said 35 amplifier tube, and means for controlling the conductivity of said amplifier tube at signal frequency.

10. In a telegraphy system, a source of direct current, a source of continuous wave energy to be keyed comprising an electron discharge tube having electrodes connected in alternating current circuits and in a direct current circuit including a non-linear resistance in series with 40 said source of direct current, an amplifier tube having a cathode connected to a point on said non-linear resistance positive relative to ground or equivalent potential and an anode connected to said direct current source whereby said cathode is held at a substantially fixed potential relative to ground due to the continuous operation of said discharge tube, means for impressing wave energy from said discharge tube on said 45 amplifier tube, a keying tube having an anode direct current circuit including an impedance interconnecting an electrode in said amplifier with said source of direct current, and means for varying the conductivity of said keying tube at signal frequency. 50
